(57) **CLAIM**

The ornamental design for a light fixture having a solar panel, as shown and described.

DESCRIPTION

FIG. 1 illustrates a front perspective view of a light fixture having a solar panel showing my new design;

FIG. 2 illustrates a front elevational view thereof;

FIG. 3 illustrates a rear elevational view thereof;

FIG. 4 illustrates a right side elevational view thereof;

FIG. 5 illustrates a left side elevational view thereof;

FIG. 6 illustrates a top plan view thereof; and

FIG. 7 illustrates a bottom plan view thereof.

FIG. 8 illustrates another front perspective view of a light fixture having a solar panel showing my new design;

FIG. 9 illustrates a front elevational view thereof;

FIG. 10 illustrates a rear elevational view thereof;

FIG. 11 illustrates a right side elevational view thereof;

FIG. 12 illustrates a left side elevational view thereof;

FIG. 13 illustrates a top plan view thereof; and,

FIG. 14 illustrates a bottom plan view thereof.

The broken lines shown in the Figures illustrate portions of the light fixture having a solar panel that form no part of the claimed design.

1 Claim, 14 Drawing Sheets
